UNITED STATES PATENT OFFICE

160,660

BOTTLE

Heinrich Riemerschmid, Munich, Germany, assignor to Anton Riemerschmid Kommanditgesellschaft, Munich, Germany, a limited partnership

Application June 7, 1949, Serial No. 3,090

In Germany December 11, 1948

Term of patent 14 years

(Cl. D58—6)

To all whom it may concern:

Be it known that I, Heinrich Riemerschmid, a citizen of Germany, residing at Munich, Bavaria, Germany, have invented a new, original, and ornamental Design for a Bottle, of which the following is a specification, reference being had to the accompanying drawings, forming a part hereof.

Fig. 1 is a side elevation of a bottle, showing my new design.

Fig. 2 is a front elevation,

Fig. 3 is a side elevation of the bottle, looking to the right of Fig. 2,

Fig. 4 is a rear elevation,

Fig. 5 is a side perspective, and

Fig. 6 is a top plan thereof.

I claim:

The ornamental design for a bottle, as shown.
HEINRICH RIEMERSCHMID.
